Primary Examiner — Mary Ann Calabrese*Assistant Examiner* — Jennifer L Rempfer(74) *Attorney, Agent, or Firm* — Craig R. Miles; CR Miles P.C.(57) **CLAIM**

I claim the ornamental design for an anchorable walled mat, as shown and described.

DESCRIPTION

FIG. 1 is a top and front side perspective view of an anchorable walled mat, embodying my new design;

FIG. 2 is a top plan view thereof;

FIG. 3 is a bottom plan view thereof;

FIG. 4 is a front side view thereof;

FIG. 5 is a rear side view thereof;

FIG. 6 is a right side view thereof;

FIG. 7 is a left side view thereof; and,

FIG. 8 is an enlarged view of a junction of the front side and the right side of the anchorable walled mat shown in FIG. 1. The broken lines shown are included for the purpose of illustrating the unclaimed portions of the article and form no part of the claim.
